UNITED STATES PATENT OFFICE.

WILLIAM A. LACKE, OF CHICAGO, ILLINOIS.

CONVEYER AND PILER FOR LARGE SHEETS.

Application filed June 3, 1921. Serial No. 474,795.

To all whom it may concern:

Be it known that I, WILLIAM A. LACKE, a citizen of the United States, residing at Chicago, in the county of Cook and State of Illinois, have invented a certain new and useful Improvement in Conveyers and Pilers for Large Sheets, of which the following is a specification.

This invention, a mechanism for conveying large heavy sheets of material from one point to another and then accurately piling them, is especially adaptable for use in handling large hot metal sheets in the general mechanism for corrugating freight car ends and the like shown, described and claimed in my prior patent application, Serial No. 466,184, filed May 2, 1921.

The invention consists in conveyer mechanism controlled by an operator standing at a distance adapted to convey sheets of metal in a step by step motion, thus giving them time to cool at the end of each step, from one point to another distant point where they are to be piled and in means for then getting the plates off from the conveyer mechanism into an accurately formed pile from which they can be readily removed by a crane and the like. Specifically the invention consists in many features and details of construction hereafter more fully set forth in the specification and claims.

Referring to the drawings in which like numerals designate the same parts throughout the several views.

Figure 1 is a general plan of the mechanism of this invention shown applied to and used in connection with the general mechanism of said prior application.

Figure 2 is a sectional detail view on the line 2—2, Figure 1.

Figure 3 is a side view of the sheet moving mechanism taken at approximately the line 3—3, of Figure 1.

Figure 4 is an end view of the conveying mechanism taken at approximately the arrow designated 4 in Figure 1, showing a side view, of a sheet piling mechanism in the position its parts assume when they are just ready to deliver a sheet from the conveyer to the pile.

Figure 5 is a changed position view of Figure 4 showing the sheets being piled.

Figure 6 is an end view taken on the line 6—6, Figure 4.

Figure 7 is a sectional detail view of a

control valve used in operating the mechanism.

As is fully set forth in said prior application and in another copending application, Serial No. 471,708, the metal sheets 16 are ordinarily supplied for the mechanism of this invention by delivery from a corrugating press 10 onto and along supporting rails 12 to position 16, the sheets being pulled along, one at a time, to said position by gripping tong mechanism 14—15 fully described in said applications.

The problem of this invention is to convey the plates one at a time from position 16 thru the successive positions 16^a, 16^b, 16^c, and 16^d to position 16^e where they are piled; giving sufficient time in each position so that a practically red hot plate in position 16 is cool enough in position 16^e for piling.

In accomplishing this object a pair of stationary rails 18 are permanently mounted on supports 20 and 22. They extend from a point close to a plate 16 on rails 12 to a point adjacent to the piling mechanism. Inside the rail 18, parallel to them, and longitudinally slidable across the supports 20, are two other rails or bars 24 having their upper surfaces slightly below the tops of the rails 18 (Figure 3) so that these rails 20 may be freely reciprocated backwards and forward under plates 16 resting in the various positions on the rails 18. These two rails 24 are permanently attached to a cross-head 26, reciprocatable by the movement of the piston rod 28 under the control of a piston 30 movable in the horizontal cylinder 32 adapted to be controlled by an operator, who by suitable mechanism, not entering into this invention causes the admission and discharge of air through supply pipe 34 leading to the cylinder. Cylinder 32 is of such a length that the crosshead 26 and consequently the rails 24 travel a distance equal to the distances between the successive positions 16, 16^a, etc., of the plates along the rails 18. The rails 24 carry a ratchet dog 36, normally pressed upward by spring 38 to the position shown in Figure 3 in which the working point 38 of the dog will engage the edge of an adjacent plate 16 resting on rails 18. The springs are of such a tension that when rails 24 are moved to the left as viewed in Figure 3 the dogs 36 push the plates they then engage and when the rails 24

are moved to the right they click under any

plate which may be above them. These dogs 36 are spaced apart on rails 24 the exact distance the adjacent plate is to be moved at each reciprocation of the rails 24 by cylinder mechanism 32.

- In the operation of this part of the mechanism a plate is delivered in the general manner described to position 16 of Figure 1. Assuming that the rails 24 are also in the 10 position of that figure with the dogs 36 at the end of the rail outside the plate 16, viz, above as shown in Figure 1, the operator now admits air into the cylinder 32 to drive the piston 30 downward as viewed in Figure 15 1, thus carrying the rails 24, consequently the end dogs 26 and plate 16 attached to them and the plate 16 resting against those dogs downward as viewed in Figure 1 until plate 16 reaches the position 16^a of Figure 1. 20 The operator now reverses the direction of motion of piston 30 with the result that the dogs 36^a, which had until this time been always below plate 16 as viewed in Figure 1, slide under the plate in position 16^a without 25 moving it, viz, move under it from the position of 36^b to the position of 36^a, at the same time that the end dogs 36 are returning to the normal position of Figure 1 ready to receive a new plate. When a second plate is 30 now placed in the position 16, and the cylinder is again operated to move the rails 24 downward, dogs 36^a carry the first original plate from positions 16^a to position 16^b and the end dogs 36 carry the second plate from 35 position 16 to positions 16^a. On again manipulating the cylinder mechanism to cause upward movement of rails 24 as viewed in Figure 1, each pair of the dogs which are below any adjacent plate as viewed in Figure 1, slip under it until they are above that plate and are ready to pull it downward on the next movement of the rails 24 downward. Repeating the operation ultimately puts a plate in each of the positions 16 to 45 16^b, whereupon they are moved, step by step by the mechanism described in a continuous procession so long as plates are supplied at position 16 and removed at position 16^b.

- While we have described rails 24 as always 50 moved to extreme upward position before a plate is moved to position 16, nevertheless the placing of plates does not have to wait for the positioning of the rails because on any upward movement of rails 24 the end dogs 36 will slip under a plate, either in position 16 or while being there positioned, just as the other dogs slip under their adjacent plates as described. The movable rails 24 are so positioned with reference to the air cylinder 32 that the lower ends of the rails as seen in Figure 1 only advance beyond the ends of the rail 18 and therefore never interfere with the plate in position 16^b as it drops to position 16^a, as hereafter described. 55 60 65 Each of these rails 24 is however, equipped

at its lower end, as viewed in Figure 1, with latch dogs 36 which, as shown in Figure 1, engage the plate in position 16^a and as the rails are moved toward the piling mechanism carry the plate off from the rails 18 into 70 the position 16^b.

At the end of the path of travel of the plates, as described, and so located as to handle the plate delivered to position 16^b is a piling mechanism which will now be described. 75

Transversely of the end of rails 18 (the lower ends as viewed in Figure 1) are placed suitable foundation supports 40 and 42 across which are mounted low level rails 44 80 running in the same general direction as rails 18 on which the final pile of plates 16^c rest until such time as they are carried away by a crane or other mechanism not entering into this invention. The supports 40 and 42 are on opposite sides of pit 46 below the rails 44. On the bottom of this pit and on opposite sides of the rails 44 are suitably secured base castings 48, each having pivoted to it at 50 an upwardly extending 85 swinging lever arm 52 having in the upper portion an outwardly curved U-shaped section 52^a adapted to pass around and clear the ends 54 of the pile of plates 16^c said designation being applied to the piled body of 90 plates which result from dropping the plates one at a time from the position 16^b downward.

As clearly shown in Figure 1 there are two of these vertically extending levers 52 100 at each end of plates in the position 16^b so that, as shown in Figure 2, supports are formed at all four corners of the pile of plates whenever said levers are swung to upright position, as shown in Figure 4. 105 When, however, these levers are swung outwardly from the center of the plate to the position shown in Figure 5, they leave sufficient clearance between levers on opposite ends of the plates so that a plate in position 110 16^b can drop vertically onto the pile 16^c.

One of the problems of the invention is to provide means for swinging the levers 52 outward from under a plate 16^b with sufficient rapidity so that the plate is not disturbed by the movement of the lever and can fall into the pile. In accomplishing this object a pair of oppositely disposed air cylinders 56 are placed upon suitable base supports 58, standing on the bottom of pit 115 46. Extending from each cylinder toward its adjacent end of the pit 46 is a piston rod 60, carrying a crosshead 62 pivotally connected to the two lever arms 52 at that particular end of the pit. The levers 52 120 are normally drawn inward from the position of Figure 5 to that of Figure 4 by a spring mechanism 64 provided for the purpose. They are moved outward against the action of such spring mechanism whenever 125 130

air is admitted to the ends of the cylinders 56 from which the piston rods do not project behind the pistons 66. Means for so admitting air behind each piston is provided 5 thru a pipe 68 which enters the proper end of each of the cylinders 60, as clearly shown in Figure 4. The one pipe 68 supplying both cylinders is fed with air, or other working agent from any suitable source by 10 a main supply pipe 70. Intermediate of pipe 70 is placed a special valve mechanism shown in Figure 7 which includes a case 72, a valve 74, normally pressed onto its seat by spring 76 and provided on its opposite 15 ends with a piston rod 78 terminating in the piston 80 reciprocatable in air chamber 82 formed in the case 72, there being provided a pipe 84 leading to the side of piston 80 which is opposite of the valve 74. When 20 an operator admits compressed air, perhaps from the same source of power as that used for pipe 70 itself, thru pipe 84 to piston 80, valve 74 which is smaller than piston 80 is moved violently from its seat, thereby making a clear passage thru pipe 70 and the 25 chambers 86 and 88 of the valve mechanism. Air now rushes violently from the source of supply, thru pipe 70 and pipe 68 into the respective cylinders 56 to thus move 30 pistons 66 violently away from the center line of the pit 46 and consequently throw the upwardly extending lever arm 52 quickly from the position of Figure 4 to that of Figure 5, thereupon allowing the 35 plate in position 16° to drop, always in positions parallel to itself, into the pile 16'.

In order to prevent the cylinder mechanism from tearing itself to pieces, due to the violence of the outward movement of 40 the pistons, as described, each cylinder is provided intermediate of its length with a plurality of air holes 90 so that the air in front of the piston has a free chance to escape until these air holes are reached and that the pistons are cushioned as they pass 45 over and beyond these air holes.

In the operation of this part of the mechanism, the operator manipulates the air control by turning a suitable valve, for instance 50 valve 92 in pipe 84, so that valve 74 is closed and the lever arm 52 is in the full line position of Figure 4, and leaves the device in that position until the plate conveying mechanism previously described, places a 55 plate in position 16°. When this happens, the operator manipulates valve 92 to quickly open valve 74, thus moving the plate support and levers 52 outward to the position of Figure 5, thus allowing the plate to drop 60 to position 16'. Just as soon as the plate passes the upper ends of the levers the operator reverses the process and closes valve 74, whereupon the springs 64 return the supporting lever in position of Figure 4 ready 65 to receive another plate. This operation is

repeated after each plate is delivered to position 16° until a suitable pile of plates 16' is produced whereupon they are removed by a traveling crane or other suitable mechanism.

In the operation of the complete mechanism the tong gripping mechanism 14-15 travels along rail 94 toward and from the press 10 to at each reciprocation carry a plate from the press to position 16 on the 70 conveyer. From this position the plates are moved step by step along the conveyer by reciprocation of the rails 24 carrying the upwardly swinging latch dog 36 in the manner described. As the conveyer mechanism 75 delivers each plate to position 16° it is dropped down to the pile 16' in the manner described. All this may be accomplished by an operator standing at a distance and manipulating the control devices of pipes 80 84 and 84 thereby doing away with the danger and inconvenience occasioned by requiring workmen to manually manipulate these plates, particularly those of the size required for freight car ends.

The term air is used in the claims to cover any motive fluid capable of operating the mechanism.

Having thus described my invention what I claim as new and desire to secure by Letters Patent, is:—

1. In mechanism of the class described, a pair of supporting members adapted to receive and support opposite ends of a plate and selectively controllable air cylinder 100 mechanism for quickly separating said supporting members out from under said plate for the purposes set forth.

2. In mechanism of the class described, a pair of upwardly extending spaced apart 105 pivoted lever arms having U-shaped recesses adapted to pass around the ends of a pile of plates, the upper ends of said lever arms being so positioned as to support a plate clear of and above said pile, and means for 110 swinging said lever arms apart to allow the last mentioned plate to fall onto the pile, for the purposes set forth.

3. In mechanism of the class described, a pair of upwardly extending spaced apart 115 pivoted lever arms having U-shaped recesses adapted to pass around the ends of a pile of plates, the upper ends of said lever arms being so positioned as to support a plate clear of and above said pile, a pair of oppositely positioned air cylinder mechanisms one for each of said levers, and means for 120 quickly admitting air to said cylinders for the purpose of moving said levers away from each other, for the purposes set forth.

4. In mechanism of the class described, a pair of air cylinders, a pipe conveying air to said cylinders, a common valve controlling the air admitted to both of the cylinders, and a pneumatically operated mechanism for in- 125 130

stantly unseating said valve, for the purposes set forth.

5. In mechanism of the class described, a valve casing, a main supply pipe entering one side of the casing, passing thru it, and emerging from the casing from a different point, a valve inside the casing controlling the passage of air from one of the main supply pipe sources to the other, a piston 10 rod connected to said valve, a piston on said piston rod reciprocatable in a suitable chamber in the casing separate from the main air passage, and means for admitting air to said piston to move it to move said valve from 15 its seat, for the purposes set forth.

6. In mechanism of the class described, an air cylinder having a reciprocatable piston therein, there being around the cylinder a plurality of openings spaced intermediate 20 of the ends of the cylinder, and means for violently admitting air to the working end of the cylinder, for the purposes set forth.

7. In mechanism of the class described, a pair of rails on which a plurality of plates 25 may be placed to form a pile, a pair of oppositely disposed pivotally mounted vertical levers formed with U-shaped sections at its upper portions, adapted to pass around the end of the pile of plates on said rail, between 30 two positions in one of which the upper ends

of said levers support a plate above said pile, and the other of which the plate is allowed to fall onto the pile, a pair of air cylinders located below said first mentioned rail supports, a piston rod in each of said cylinders, 35 extending toward an adjacent one of said lever members and pivotally connected thereto, spring mechanism tending to normally force said pistons inward to cause said levers to assume the position in which they 40 support a plate, a piston on each piston rod in the adjacent air cylinder, means for admitting air into the cylinder on the sides of the piston which are away from the piston rods, a plurality of perforations around the 45 circumference of each cylinder near its middle, a valve mechanism controlling the admission of air thru both of said cylinders, and means for opening said valves to full capacity substantially instantly, all the parts 50 being arranged and disposed as shown and described, for the purposes set forth.

In witness whereof, I have hereunto subscribed my name in the presence of two witnesses.

WILLIAM A. LACKE.
